UNITED STATES PATENT OFFICE.

DAVID B. HANNA, OF CHICAGO, ILLINOIS, ASSIGNEE TO MASSEY CONCRETE PRODUCTS CORPORATION, OF CHICAGO, ILLINOIS, A CORPORATION OF VIRGINIA.

POLE MACHINE.

1,410,751.

Specification of Letters Patent. Patented Mar. 28, 1922.

Application filed May 22, 1919. Serial No. 298,877.

To all whom it may concern:

Be it known that J. DAVID B. HANNA, a citizen of the United States, residing at Chicago, in the county of Cook and State of Illinois, have invented certain new and useful Improvements in Pole Machines, of which the following is a specification.

This invention relates to pole making machines for making concrete poles and the like, and it has for its primary object the provision of an improved means for directly driving the pole mold.

Another object of the invention resides in the provision of an improved driving coupling so constructed that the molds may be expeditiously handled in the machine and readily coupled and uncoupled to and from the motor.

Still another object of my invention resides in the provision of an improved driving coupling which readily accommodates itself to variations in the size of the mold and also to irregularities in the mold.

The foregoing together with such other objects as may hereinafter appear, or are incident to my invention, I obtain by means of an improved construction which I have illustrated in preferred form in the accompanying drawings wherein:

Figure 1 is a side elevation of a portion of a pole machine embodying my improvements; Figure 2 is a cross section through the machine, drawn on an enlarged scale, illustrating the manner in which the mold is revolvably supported in the machine; Figure 3 is a cross section taken through the coupling on the line 3-3 of Figure 4; Figure 4 is a section taken on the line 4-4 of Figure 5 illustrating the coupling in end elevation; Figure 5 is a side elevation of a modification of my invention; and Figures 6 and 7 are views of details thereof, Figure 6 being a section taken on the line 6-6 of Figure 5.

The general arrangement of the machine is substantially like that shown and described in my co-pending application filed May 22, 1919, Serial Number 298,876, and for the purpose of this specification it will suffice to say that the machine in general comprises a base A composed of suitable structural members 7 embedded in concrete. Suitably mounted in bearing blocks 8 in the base are pairs of spaced rollers 9, having

flanges adapted to engage tires 10 mounted on the exterior of the pole mold B, and the mold being supported on the rollers 9 by means of yoke-like members C, pivoted on the shafts 10 of the rollers 9 on one side of the machine, said member C being provided with rollers 11 and 12 adapted to engage the tires 10.

Referring now to the driving mechanism, it will be seen that I have provided a motor D which is carried on a suitable base 13 supported on the main frame work or base A at an end thereof opposite an end of the mold. Rotatably mounted on the shaft 14 of the motor D I provide a sleeve-like driving coupling E having an outwardly extending annular flange or lip 15, the inside diameter of which is considerably larger than the outside diameter of the mold B. Adjustably mounted in the coupling, I provide a plurality of radial centering or adjusting blocks 16 adapted to engage flattened portions 17 formed on the periphery of the end section of the mold. The blocks 16 form the driving connection between the coupling E and the mold, and they are forced into tight engagement with the mold by means of the studs 18. This arrangement in addition to providing a driving connection, permits of the coupling being adjusted to molds of different sizes, and also permits the coupling to be accommodated to irregularities in the mold. If desired the lower pair of blocks 16 may be rigid.

As described in the aforesaid co-pending application, the sectional halves of the mold B are bolted together, with such reinforcement as may be employed mounted in the interior thereof, after which the mold is partially filled with concrete. The mold is then picked up by a hoist or other suitable mechanism and placed in the machine with the tires 10 resting upon the flanged rollers 9, it being kept in mind that for this purpose the yoke-like members C are swung to one side about the shafts 10 as an axis. In placing the mold in position, the end next the motor is inserted into the couplings E, and thereafter blocks 16 are adjusted so as to tightly engage the mold, and the members C are swung into position. The mold is now rotated until the pole is formed, after which the blocks 16 are loosened, the members C swung to retracted position, and the

mold removed, when the machine is ready for the reception of another mold.

In some cases it may be desirable, in order to facilitate assemblage, to mount the coupling member D in such manner that it may be retracted to an inoperative position permitting the mold to be lowered into position, properly engaging the rollers 9, and afterwards advanced to fit over the end of 10 the mold in the manner previously described. For this purpose a splined connection such as shown at 19 in Figure 3 may be utilized.

In Figures 5, 6 and 7, I have illustrated a modified form of driving connection between the mold the motor. In accordance with this embodiment of my invention, the shaft 14 of the motor has a circular member E' keyed to an end thereof, such member having a plurality of grooves 21 which are 20 preferably given a taper as shown in Figure 6. The mold is provided at an end thereof with a corresponding member E² which is provided with a plurality of tongues 22 adapted to fit the grooves 21. By this arrangement it will be seen that it is possible 25 to establish the driving connection very

readily as the mold is being lowered into position on the bed of the machine.

I claim:

1. A pole making machine comprising in combination a support, a mold supported therein for rotation, a motor opposite an end of the mold and a coupling member adapted to receive an end of the mold, together with a variable means for releasably securing the 35 mold and coupling together.

2. A pole making machine comprising in combination, a support, a mold supported therein for rotation, a motor opposite an end of the mold and a coupling member adapted 40 to receive an end of the mold, said coupling being mounted for longitudinal movement with reference to the mold.

3. A pole making machine comprising in combination a rotatable mold, a motor opposite an end of the mold, and a coupling device adapted to receive an end of the mold, 45 said device being so constituted as to variably and releasably secure it to the mold.

In testimony whereof, I have hereunto signed my name.

DAVID B. HANNA.
